BRASSIÈRE

Arthur Vale and Harold L. Rothstein, New York,
N. Y., assignors to La Trique Brassiere Company,
New York, N. Y., a copartnership

Application May 19, 1952, Serial No. 288,622

2 Claims. (Cl. 2—42)

1

Our invention relates to a new and improved brassière.

One of the objects of our invention is to provide a brassière whose body is made of light and easily bendable and non-elastic cloth or other material, which is reinforced so as to provide a resilient cup-shape.

Another object is to provide such article with cup-pads which are connected to the body of the garment by improved means.

Another object is to make an article of this type which will be non-irritating to the skin and which can be made at low cost.

Other objects and advantages and features of the invention are stated in the annexed description and drawings.

Fig. 1 is a rear perspective view of the improved device. The parts at the rear of one cup have been partially separated from the body of the garment, in order to show the internal structure.

Fig. 2 is a front perspective view of the improved garment.

Fig. 3 is a section on the line 3—3 of Fig. 2.

Fig. 4 is an elevation of the intermediate body panel to which the tape reinforcement is applied. Said reinforcement is applied at the inner face of said intermediate panel.

Fig. 5 is an elevation of the front and rear panels of the garment.

Fig. 6 is an elevation of a pocket panel of the garment.

Fig. 7 is a rear view of a pad.

The garment comprises identical body portions 1 and 1a, which are provided with respective identical cups C and Ca. Each cup C comprises a front panel 2, an intermediate panel 3, a rear panel 5 and a pocket which is formed at the inner face of each cup C by means of a pocket panel 4. A pad P is located in each pocket. Each pad P may be made of soft and resilient foam rubber, or other material. Each pad P has a tapered front wall, which is of substantial conical shape, preferably with a blunt tip. Each pad P may have a concave rear wall. The pads P are identical and they are slightly oversized relative to their pockets so that they are held in position while said pads P are slightly bent out of normal shape. A part of each front wall of each pad P abuts the respective pocket panel. The top portion of each pad P is spaced from the apex of the respective pocket panel 4. Fig. 3 is substantially to scale and illustrates the construction in each half of the garment.

The panels 2, 3, 4 and 5 may be made of light

mesh material, which may be loosely woven material. Such material is very light and porous.

Separate rings of cloth tape T are sewed to the inner face of the intermediate panel 3, by means of stitches Ta, which also penetrate the front panel 2 and the panel 3, in order to connect said panels 2 and 3 to each other by means of said stitches Ta. In the assembled garment, the respective rings of tape T are located between the inner panel 3 and the inner cover panel 5, thus preventing any irritation from said rings of tape T. This tape T may be a woven bias-cut tape, which is longitudinally stretchable and elastic.

The original flat cut shapes of the panels 2, 3, 4 and 5 are shown in Figs. 3, 4 and 5. The panel 3 has original separate edges 12 and 12a. The panel 2 has original separate edges 14 and 14a. The panel 5 has original separate edges 16 and 16a.

The panel 4 has original separate edges 17 and 17a.

The intermediate panel 3 is put on top of the front panel 2, with the edges of said panels in registration. Said panels 2 and 3 may be temporarily connected.

The separate rings of tape T are then placed on top of the top face of the panel 3, and the tape is sewed in respective separated rings to the panels 2 and 3, by means of the rings of stitches Ta. This can be done in an ordinary sewing machine, while the tape T of each ring is under any selected tension.

The ends of each tape ring terminate at the respective aligned edges 12—14 and 12a—14a. The ends of each tape ring may extend slightly beyond said aligned edges.

The stitching of these tape rings to panels 2 and 3 provides cups C of tapered and substantially conical contour; when the edges 12, 12a, 14 and 14a are stitched to each other to form the seams S and Sa.

The invention is not limited to this method of fixing the tape rings to panels 2 and 3.

The edges 16 and 16a of rear panel 5 are connected by stitches to form seams 55. The edges 17 and 17a of pocket panels 4 are connected to each other by similar stitches. The bases of pads P are then placed upon the respective panels 5 and the respective pocket panels 4 are then stitched to the respective panels 5 by respective circular rows of stitches 18.

The edges of the assembled panels 2, 3 and 5 are then bent inwardly to provide top and bottom abutting folds 2a, 3a, and 5a. Stitches 7

and 1a connect the top folds 2a, 3a and 5a to the folds 6a and 6b of a top tape 6.

Stitches 30 and 30a connect the bottom folds 2a, 3a and 5a to a bottom tape 9, which is folded like tape 6.

The respective stitches 30a in the body portions 1 and 1a, also connect the bottom folded edges of the panels 2, 3 and 5 to the supplemental strips 10 and 10a, which are also made of light mesh material. The central seam 19 connects the body portions 1 and 1a, the top and bottom tapes 6 and 9, and the elastic strips 11 and 11a.

These strips 11 and 11a are stitched to bottom tapes 9 and to strips 10 and 10a.

The garment has the usual shoulder straps 20 and 20a. It also is provided with the usual fastening ends which include elastic 24, eyes 22, and hooks 23.

Fig. 5 shows a difference in angularity between the edges 14-14a and 16-16a, in order to allow for the different shapes of these panels in the assembled garment.

At their junctions at central seam 19, the tapes 6 and 9 may be connected to each other by supplemental tape strips, in order to reinforce the garment at its central vertical seam 19.

In this preferred construction, to which the invention is not limited, all the parts may be made of cloth, with the exception of pads P and the elastic strips 11, 11a and 24.

We have disclosed a preferred embodiment of our invention, but numerous changes and omissions and additions and substitutions may be made without departing from its scope.

The invention also includes parts of the complete device. The body of the improved garment can be easily bent and twisted, because it is free from stiff material. However, the easily bendable and concentric reinforcing rings of tape cause each cup-section to yieldingly maintain the desired cup-shape.

For convenience, the assembled panels 2 and 3 may be designated as the outer layer of the respective cup-section and the panel 5 may be designated as the inner layer, and the panel 4 may be designated as the intermediate layer.

We claim:

1. A brassière comprising a body section made

of bendable cloth and including a central, forwardly protruding cup-section, said cup-section having reinforcing and substantially concentric rings affixed to the rear face thereof, said rings being made of bendable cloth tape of sufficient stiffness to maintain said cup-section normally in its forwardly protruding form, said cup-section also having a cloth backing layer extending across the rear face thereof and secured thereto outwardly of said rings, a cloth pocket panel fixed to the front face of said backing layer to form a pocket, and a bendable and resilient pad located in said pocket, said pad being larger than said pocket and being held in forwardly protruding cup-shape thereby, said pad nesting loosely within the central portion of said outer cup-section and being of substantially smaller area than said outer cup-section and being substantially located wholly forwardly of the ring of greatest diameter.

2. A brassière comprising a body section made of bendable cloth and including a central, forwardly protruding cup-section, said cup-section having reinforcing and substantially concentric rings affixed to the rear face thereof, said rings being made of bendable cloth tape of sufficient stiffness to maintain said cup-section normally in its forwardly protruding form, a pad member, and means securing the respective upper and lower portions of said pad member to the rear face of said body section, said pad member comprising a forwardly protruding, cup-shaped pad made of bendable and resilient material, said pad nesting loosely within the central portion of said cup-section and being of substantially smaller area than said cup-section and being substantially located wholly forwardly of the ring of greatest diameter.

ARTHUR VALE.
HAROLD L. ROTHSTEIN.
